Fig. 2.

Fig. 3.

A line drawing of a garment, possibly a dress or tunic, shown from the waist up. The garment has a high, notched collar. Numbered labels are placed on various parts of the garment: 15 is on the right shoulder; 16 is on the left shoulder; 17 is at the top right corner of the collar; 18 is on the left side of the chest; 19 is on the right side of the chest; 20 is on the right shoulder; 21 is on the right side of the waist; 22 is on the left side of the waist; 23 is on the right side of the waist; 24 is on the left side of the waist; and 25 is on the right side of the waist. There is also a small label '19-' at the bottom left.

UNITED STATES PATENT OFFICE.

JOSEPH CARTER HAWLEY, OF BLACKSBURG, VIRGINIA.

SUIT OF ARMOR.

1,269,930.

Specification of Letters Patent. Patented June 18, 1918.

Application filed February 6, 1918. Serial No. 215,617.

To all whom it may concern:

Be it known that I, JOSEPH CARTER HAWLEY, a citizen of the United States, residing at Blacksburg, in the county of Montgomery, 5 State of Virginia, have invented a new and useful Suit of Armor; and I do hereby declare the following to be a full, clear, and exact description of the invention, such as will enable others skilled in the art to which 10 it appertains to make and use the same.

This invention relates to an improved suit or coat of armor for use by soldiers in general, and particularly by those in the first line trenches and by aviators, in fact 15 by all in every branch of the service, and one of the objects of the invention is to provide an improved, efficient and practical armor of this kind, which will act as a thorough and complete protection to the wearer's 20 body.

A further object of the invention is to provide an entire suit or coat of armor for the wearer's or soldier's body and constructed in sections, said sections having 25 overlapping joints, the underlapping parts of which having elastic means, in order to hug the various parts of the body tightly.

A further object of the invention is to provide overlapping parts of said joints 30 with movable sections, which are joined by elastic means, whereby said sections may give and accommodate themselves to the movements of the body of the wearer.

A further object of the invention is to 35 provide a suit or coat of armor having a body section to fit the body of the wearer, the upper part of the body section having a shoulder and neck elastic section, adapted to stretch over the arms, the shoulders and 40 the head of the wearer when the body section is slipped onto the body of the wearer, the arms of the wearer having been moved straight upwardly over the head of the wearer, so as to pass through the openings 45 of the elastic shoulder section.

A further object of the invention is the provision of a suit or coat of armor having a helmet section constructed of two parts hingedly united, so as to fit the head of the 50 wearer, said helmet section having cape or shoulder sections hingedly connected to the helmet, and being in turn elastically united, so as to give and accommodate themselves to the wearer's body.

55 In practical fields the details of construc-

tion may necessitate alterations falling within the scope of what is claimed.

The invention comprises further features and combination of parts as hereinafter set forth, shown in the drawings and claimed. 60

In the drawings:—

Figure 1 is a view in perspective, showing the application of the suit or coat of armor as applied to the body of a wearer.

Fig. 2 is a vertical sectional view through 65 the armor.

Fig. 3 is a detail perspective view of the body section of the armor.

Fig. 4 is an enlarged detail perspective view of the trouser section of the armor. 70

Fig. 5 is a detail sectional view on line 5—5 of Fig. 1, showing the connections between the sleeve sections and the elastic shoulder sections, and illustrating how the cape or shoulder sections of the helmet overlap the upper part of the sleeve section. 75

Fig. 6 is a detail sectional view showing the sections of one of the legs of the trousers.

Referring more especially to the drawings, 1 designates the body section of the armor, 80 2 denotes the legs of the trouser section. The trouser section of the armor is provided with a suitable trunk section 3 constructed of any suitable elastic material preferably rubber, and which is secured by rivets or 85 the like 4 to the trouser legs 2. The lower ends of the trouser legs having hingedly connected thereto as shown at 5 movable sections 6, which are arranged edgewise to each other, and are connected or joined by 90 elastic bands 7, whereby the sections 6 may give and accommodate themselves to the movements of the knees of the legs of the wearer. The legging sections 8 are of sufficient size in cross section, to permit the legs 95 of the wearer and the feet to easily pass therethrough, and yet when said sections are on the legs of the wearer they will fit in order to avoid excessive looseness of play. Secured by rivets 10 or the like to the upper 100 parts of the legging sections are knee-cap sections 9, which may be constructed of any suitable elastic material preferably rubber, so as to snugly fit the leg just above the knee, and to give readily as the knee bends, and 105 yet act to hold the sections 8 in place. The sections 6 of the legs 2 of the trousers overlap the elastic knee cap sections 9, in order to protect those portions of the legs of the wearer. The lower marginal edge of the 110

body section 1 has hingedly connected thereto as at 11 movable sections 12, which are united edgewise by means of a suitable elastic band 13. These sections 12 overlap the 5 trunk section 3 in order to protect the same, and are capable of giving and accommodating themselves to the movements of the body. Secured to the upper marginal portion of the body section by means of rivets or 10 the like 14 is a shoulder section 15, constructed of any suitable elastic material preferably rubber. This shoulder section has arm parts 16 and a neck portion 17. In attaching the body section 1 to the body it 15 is passed telescopically down over the body of the wearer, the arms having been disposed perpendicularly, so as to pass through the arm parts 16, whereby the head may pass through and stretch the neck portion 17. 20 Each sleeve of the armor consists of the sections 18 and 19. The section 18 is secured by rivets or the like 20 to an arm part 16, and its lower marginal edge has connected to it hingedly as shown at 21 the movable 25 sections 22, which are united edgewise by an elastic band 23, whereby the sections 22 may give and accommodate themselves to the bending of the elbow. The section 19 of the sleeve has secured to its upper part an 30 elastic portion 24, which hugs the arm just above the elbow, and this portion 24 is covered by the sections 22. The helmet section 25 of the armor consists of two parts, the back head part 26 and the front head 35 and face part 27, which are hingedly united as at 28, and adapted to be latched by the hook or other fastener 29, when fitted to the head of the wearer. The upper part of the helmet section as shown corresponds to 40 the shape of a soldier's hat or cap, and the lower part of the helmet section has a neck portion 30, to correspond and fit the shape of the neck of the wearer. Hinged at 31 to the lower marginal edge of the neck portion are 45 movable sections 32 to overlie the shoulder section 15 of the armor so as to protect the same. These sections 32 are united edgewise

by means of an elastic band 33, in order to give and accommodate themselves to the movements of the shoulders of the body of 50 the wearer.

The invention having been set forth what is claimed as new and useful is:—

1. In a coat or suit of armor, a helmet section, a body section, and trunk and 55 trouser section, said body section having sleeves, said parts consisting of sections, said sections having overlapped joints, the overlapping parts comprising movable edgewise elastically united parts, the underlapping 60 portions of the joints consisting of elastic material to tightly hug various parts of the body of the wearer.

2. In a suit or coat of armor, a helmet section comprising hingedly united half 65 parts, a body section, said body section having sleeves, separately consisting of sections, trunk, and trouser sections, all of said sections having overlapping joints, the overlapping parts, each consisting of movable 70 edgewise elastically united portions.

3. A suit or coat of armor, comprising a helmet section consisting of hingedly united parts, a body section having sleeves, each 75 consisting of sections, the body section having an elastic shoulder part, the neck of the helmet having hingedly connected to its lower marginal edge movable parts edgewise elastically united overlying the elastic shoulder parts of the body section, a trouser section 80 comprising a trunk part and trouser legs, each leg consisting of sections, the trunk part being constructed of elastic material, the lower marginal edge of the body section having movable members edgewise 85 elastically united overlying the trunk part, all of said sections being separably united.

In testimony whereof I have signed my name to this specification in the presence of two subscribing witnesses.

JOSEPH CARTER HAWLEY.
